UNITED STATES PATENT OFFICE.

AXEL W. CARLSON, OF WORCESTER, MASSACHUSETTS, ASSIGNOR TO COPPUS ENGINEERING AND EQUIPMENT COMPANY, OF WORCESTER, MASSACHUSETTS, A CORPORATION OF MASSACHUSETTS.

VALVE.

1,408,340.

Specification of Letters Patent. Patented Feb. 28, 1922.

Application filed August 22, 1917. Serial No. 187,729.

To all whom it may concern:

Be it known that I, AXEL W. CARLSON, a citizen of the United States, residing at Worcester, in the county of Worcester and 5 Commonwealth of Massachusetts, have invented a new and useful Improvement in a Valve, of which the following, taken in connection with the accompanying drawings, is a specification.

10 The present invention relates to valves, and has particular reference to a device of this class adapted to regulate and proportion the flow of steam, water or the like, according to a predetermined mode of operation.

15 In the present embodiment of my invention, I have illustrated the same in its application to a turbine operated fan blower, of the type adapted for the creation of an artificial draft, to maintain, for instance, a pressure in the ash pit of a steam boiler furnace. It is to be understood, however, that its use is not to be confined to the above or any other particular combination and arrangement of 20 operating devices, except in so far as is determined by the scope of the claims annexed hereto.

25 The essential features of my invention are fully set forth in the following description and illustrated in the accompanying drawings, in which—

Fig. 1 is a view, partly in vertical central section, of the apparatus embodying my invention.

30 Fig. 2 is a section on the line 2—2, Fig. 1. Similar reference characters refer to similar parts in both figures.

Referring to the drawings, I have shown a steam turbine wheel 1, of ordinary construction, having blades 2 against which a plurality of jets of steam are directed to impart rotation to said wheel, in the usual manner. The wheel 1 is carried upon a shaft 3 and is disposed within an inclosing casing 4, which is supported, by means of struts 5, from a casing 6, constituting a conduit for the air set in motion by a fan 7 mounted upon the other end of the shaft 3 and disposed near the mouth of said casing 6.

35 The construction and arrangement of the parts which form the journal bearings for said shaft, and involve the exclusion of leaking steam or water from said journal bearings, form no part of the present invention,

and hence a detailed description of the same 55 is unnecessary. The present invention is concerned only with the means for controlling and distributing, in the manner herein-after set forth, the steam exhausted from the turbine casing 4.

The exhaust aperture of the casing 4 is preferably constituted by an elbow 8, leading from the interior thereof in the direction of the open mouth of the casing 6. A short length of pipe 9 has a reduced nipple 10 60 which is entered in said elbow, and a similar pipe 11, opposite the pipe 9, has a nipple 12 which is threaded into the bore of a passage 13 formed in the wall of the casing and opening into the interior of said casing 6 at 65 14, contiguous to the fan 7. The discharge opening 14 of the passage 13 is directed into the casing 6 at an oblique angle to the axis of the fan 7, so that the movement of the air through the conduit by said blower in the 70 direction of the arrow *a* will induce a current through the passage 13 in the direction of the arrow *b*, thereby diminishing the steam pressure upon the exhaust side of the wheel 1 in the casing 4, and causing the 75 exhaust steam to become thoroughly intermingled with the air set in motion by said fan.

The pipe 11 provides a stationary disk or plate 15, having a series of equidistant segmental apertures 16 therein, in the present 80 instance four in number. The said apertures 16 are disposed apart from each other at angular distances substantially equal to the angular extent of each aperture, for a purpose hereinafter set forth. A tubular inclosure 17 connects the pipes 9 and 11, as shown in Fig. 1, being suitably secured thereto. A sleeve 18 having a turning fit within inclosure 17, is disposed therein between the ends of pipes 9 and 11. Said sleeve is open at its 85 end adjacent the elbow 8, and is formed at its end adjacent the plate 15 with a head 19, seating against said plate and having a series of segmental apertures 20 corresponding in number, size and arrangement to the apertures 16 of the plate 15.

The inclosure 17, substantially midway of its length, provides a lateral opening 21, to which is connected a pipe or conduit 22 leading to any apparatus designed to employ exhaust steam, such, for instance, as a heating system, or the like. The sleeve 18 has a port 23 adapted to register with the opening 21

when said sleeve is turned into a position in which the apertures 20 are carried out of alignment with the apertures 16, as herein-after set forth. The sleeve 18 supports an interior web 24, to which is secured a stem 25, passing through a stuffing box 26 in the casing 4, and having on its outside end a rectangular head 27, or the like, to facilitate its engagement by a wrench when the angular position of the sleeve 18 is to be adjusted. The plate 15 and the head 19 are held in close contact by the ends of pipes 9 and 11, which permit free rotation of said head with respect to said plate, but serves to prevent axial movement of said parts and the consequent leakage of steam between their contacting surfaces.

In the operation of my improved mechanism, the disposition of the sleeve 18, wherein the apertures 20 of the head 19 lie in register with the apertures 16 of plate 15, thereby affording a free passage of the exhaust steam to the casing 6, involves a disposition of the port 23 just removed from overlapping relation to the opening 21 of the inclosure 17. As the sleeve is turned from the position above described, the port area available for the passage of steam to the casing 6 is diminished, while the amount of overlap between the port 23 and opening 21 is correspondingly increased, permitting a portion of the steam to pass through the pipe 22 to the devices at the other end thereof. The invention, therefore, provides a means whereby the flow of exhaust steam from the turbine to the blower conduit may be controlled, as desired, and may be entirely cut off if, for any reason, the commingling of such steam with the air flowing through the conduit becomes objectionable. At the same time, and notwithstanding the throttling of the normal steam passage to the casing 6, the construction insures against the building up of a back pressure calculated to interfere with the operation of the turbine wheel, since the opening 21 rendered available in increasing proportion as the plate openings 16 are throttled, affords a free exit of the steam from the sleeve 18.

The previously mentioned arrangement and proportioning of the apertures 16 and 20, wherein the angular distance between such apertures is made to correspond substantially to the angular extent of each aperture, affords the maximum port area through the plate 15 and head 19, which can be completely opened and completely closed by relative movement between said plate and head, as will be clearly apparent.

In order to confine the movement of sleeve 18 within the proper limits, a stop 29 may be provided, for coaction with the opposite edges of opening 21, to prevent the port 23 from being turned beyond its above de-

scribed operative and inoperative positions 65 with respect to the opening 21.

I claim,

1. The combination, with a tubular member having one end open and carrying at the other end a plate having a series of openings, of a second tubular member telescoped within said first tubular member and providing a passage for the flow of pressure fluid, said second member having an end closure in contact with said plate, with a series of openings therein corresponding to the openings of said plate, means for causing relative rotation between said members to bring said series of openings into and out of register, and means provided in said tubular members for discharging pressure fluid from said passage when said openings are out of registration.

2. The combination with a tubular member, of a second tubular member telescoped within the first tubular member, and having a longitudinal passage for the flow of a pressure fluid medium and a lateral port for the discharge of the fluid pressure medium, a valve mechanism for closing said longitudinal passage having an opening therethrough equivalent to the opening of said lateral port, and means for the simultaneous opening and closing of said valve mechanism and of said lateral port, whereby a uniform effective area for the discharge of the pressure fluid medium from said second tubular member is maintained.

3. The combination with a tubular member having a side opening, of a stationary plate 100 extending diametrically across said tubular member and having an aperture for the passage of a fluid pressure medium therethrough, a rotatable sleeve having a side opening journalled in said tubular member 105 and provided with an apertured plate extending diametrically across said sleeve in contact with said stationary plate, and means for rotating said sleeve to divert the movement of the pressure medium through the 110 side opening of said tubular member.

4. The combination with a tubular member having a longitudinal passage therethrough of a fluid pressure medium, said tubular member having a side passage, of a 115 sleeve journalled in said tubular member provided with an aperture corresponding with the side passage of said tubular member, means for rotating said sleeve to open and close said side passage, and means carried by said sleeve for closing the longitudinal passage through said tubular member as said side passage is opened.

Dated this 14th day of August 1917.

AXEL W. CARLSON.
